Inventor:

John Kirby Jr.

UNITED STATES PATENT OFFICE.

JOHN KIRBY, JR., OF DAYTON, OHIO, ASSIGNOR TO UNITED STATES HEADLIGHT COMPANY, OF BUFFALO, NEW YORK, A CORPORATION OF NEW YORK.

FOCUSING DEVICE.

1,295,524.

Specification of Letters Patent. Patented Feb. 25, 1919.

Application filed September 12, 1918. Serial No. 253,678.

To all whom it may concern:

Be it known that I, JOHN KIRBY, Jr., a citizen of the United States, residing at Dayton, in the county of Montgomery and State of Ohio, have invented a certain new and useful Improvement in Focusing Devices, of which the following is a specification.

My invention relates primarily to electric headlights and has for its purpose to provide mechanism for adjusting the filament of an incandescent lamp to the focal point of a parabolic reflector, as set forth in my pending applications, Serial Number 249,383 filed August 12, 1918, and Serial Number 251,913, filed August 29, 1918, and from both of which my present invention differentiates in certain particulars not described, or claimed therein but which will be made clear 20 in this specification and pointed out in the claims at the end thereof.

In headlights of the type to which my invention is applicable it is essential that the center of illumination be located with accuracy in respect of the focal point of the reflector and to this end my invention consists in the novel construction and combination of parts hereinafter more fully set forth and claimed.

30 The invention is illustrated in the accompanying drawings, which constitute a part of this specification and in which Figure 1 is a side view, partly in full and partly in section, of a portion of the reflector with 35 the focusing device mounted thereon and showing the stand which supports the rear end of the reflector, Fig. 2 is a rear view, partly in section, and Fig. 3 is an enlarged cross sectional view through the center of 40 movable block and the socket shank.

Like reference numerals indicate corresponding parts throughout the drawings.

1 represents a portion of the reflector, the front end of which may be mounted upon 45 any suitable slide or base, as 2, in the usual manner, not shown. A ring 3 is secured to the rear of the reflector, the apex of which is cut away at 4 leaving an opening corresponding to the inner diameter of the said 50 ring 3. At the bottom of and preferably integral with the said ring 3 there is a laterally disposed arm or bracket extension 5 having a depending screw threaded member 6, which in conjunction with the standard 7 and nuts 8 and 9 constitute means by which

the rear end of the reflector is adjustably supported upon the base 2 as more fully described in my previous applications, above referred to. The free end of the bracket 5 is provided with an interiorly screw threaded 60 boss 10 to receive a corresponding exteriorly screw threaded plug 11, projecting from a member 12, and when these parts are screwed together, as shown in Fig. 1, they are protected against displacement by means of a 65 pin 13 driven therethrough. The upper end of the member 12 is recessed to conform to the surface of a half sphere, the front and back wall being cut away at 12^a, see Fig. 2, to permit of spherical movement of a socket 70 shank presently to be described, the said recess forming a seat 14, for a holder 15, the surface of the lower portion of which conforms to the surface of the seat 14, in which the said holder is mounted. The lower end 75 of the member 12 is also rounded at 16, to conform to the surface of a portion of a sphere and through the vertical center of this member there is a passageway 17 the purpose of which will presently appear. 80 The numeral 18 designates the lamp bulb, within which is located the filament 19, the focal point of the reflector being designated at X. The lamp bulb is held in a socket 20 having a hollow extension or shank 21, 85 through which passes current conveying wires, not shown, and which is slidably mounted in a bore formed through the holder 15 above its seat in the member 12. The holder 15 is provided with an upstanding member 22 having a partially screw threaded bore therethrough, within the lower, threadless portion 23, of which operates a vertically movable block 24 having 90 its lower end curved to conform to the 95 diameter of the socket shank 21, as more clearly shown in Fig. 3.

Operative in the threaded portion 25 of the member 22 there is a corresponding exteriorly screw threaded plug 26 provided 100 with a hand wheel 27, or other suitable means by which the said plug may be turned to force its lower end against the top of the block 24 and thereby prevent movement of the shank 21 in the holder 15 until the 105 screw pressure is relieved, which is accomplished by a slight turn of the plug in the opposite direction. The screw plug 26 is provided with a vertical chamber 28, open at its lower end, within which chamber the 11

is located a coiled spring 29 having one end bearing upon the movable block 24 and its opposite end bearing against the bottom of the chamber, the function of this spring being two-fold, first, to exert yielding pressure on the movable block when the screw pressure is relieved, and thus prevent too free movement of the socket shank 21 during adjustment thereof, and second to apply tension to the screw threads thereby preventing undue movement of the plug which otherwise would be liable to occur through jolting and vibrations incident to a rapidly moving locomotive.

Depending from the bottom of the holder 15 there is a bolt or rod 30 which passes through the passage-way 17 and extends below the bottom of the member 12, passing also through a washer 31 having a seat 32 forming to and co-acting with the bearing 33 forming the bottom of the member 12, the free end of this bolt or rod being screw threaded to receive a correspondingly screw threaded hand wheel (or the equivalent thereof) 32, having provision, in the form of a body 33, for impinging the surface 34 of the washer 31, whereby turning the hand wheel in one direction will clamp the holder 15 in its seat in the member 12 and will also clamp the bearing forming the bottom of the member 12 in its seat in the washer 31, while a slight turn of the hand wheel in the opposite direction will relieve the parts so that the holder, carrying the socket and the lamp, can be moved about its spherical center within the limits of movement of the rod 30, which is controlled by the passage-way 17, and which, in the present instance, the travel of the lamp is represented as being in an orbit indicated by broken lines in Fig. 1, its longitudinal movement being accomplished in the manner previously explained.

Located within a chamber 35, formed partly in the body of the hand wheel and partly in the washer, and surrounding the rod 30 there is a coiled spring 36 which, as in the case of the spring 29, performs a dual function in that when the screw pressure is relieved it retains the parts under yielding pressure and thereby restrains them from too free or undesirable movement, and also imparts tension to the screw threads and thereby prevents undue movement of the hand wheel when the locomotive is in motion.

Supplementary to the foregoing described means for securing the holder 15 against undue movement in its seat in the member 12, and to make more certain the stability of the proper relative position of the lamp to the reflector after the same has been adjusted and fixed, two oppositely disposed tightening devices, carried by the member 12, are arranged, one on each side, substantially in line with the spherical center of the holder

15, each device consisting of a boss 37 having an annular shoulder 38, and being bored and screw threaded to receive a set screw 39, provided with a knurled wheel 40, by which the set screw is operated, a coiled spring 41 being interposed between the shoulder 38 and the said wheel 40, the function of the spring being to prevent undue movement of the set screw, the impinging end of which may be cupped to conform to the contour of the holder. The set screws are designed to be applied to the holder 15 after it has been adjusted and secured to its seat in the member 12 by the first described means.

It is to be understood that when the parts are assembled, as shown in the drawings, but little movement will be required to adjust the filament to its proper relation with the reflector.

Having thus fully described the construction and operation of my invention as the preferred manner of carrying out the same, I do not wish to be understood as limiting the invention to the specific details of construction shown and described, as it is obvious that the same may be departed from in various ways without departing from the scope and spirit of the invention.

What I claim and desire to secure by Letters Patent is:

1. In a focusing device, in combination with a reflector, a lamp and a socket therefor, a holder carrying said socket and having a bearing constituting a portion of a sphere, a member located below said holder and having a seat in which said bearing is mounted whereby said holder may be moved about its spherical center to adjust the lamp with relation to the reflector, and means operative beneath and co-acting with a spherically formed bearing constituting the bottom of said member to grip and retain said holder in such adjusted position.

2. In a focusing device, in combination with a reflector, a lamp and a socket therefor, a holder carrying said socket and having a bearing constituting a portion of a sphere, a member located below said holder and having a seat in which said bearing is mounted whereby said holder may be moved about its spherical center to adjust the lamp with relation to the reflector, means operative beneath and co-acting with said member to grip and retain said holder in such adjusted position, and oppositely disposed auxiliary tightening devices carried by said member adapted to engage said holder at points approximately in line with the center horizontal line of said shank.

3. In a focusing device, in combination with a reflector, a lamp and a socket therefor, a holder carrying said socket and having a bearing constituting a portion of a sphere, a member located below said holder and having a seat in which said bearing is

mounted whereby said holder may be moved about its spherical center to adjust the lamp with relation to the reflector, a support for said member, and means operative beneath 5 and co-acting with a spherically formed bearing constituting the bottom of said member to grip and retain said holder in such adjusted position.

4. In a focusing device, in combination 10 with a reflector, a lamp and a socket therefor having a shank extending therefrom, a holder carrying said socket whose shank is movable longitudinally in the holder, means for securing the socket against such 15 movement, said holder having a bearing constituting a portion of a sphere, a member located below said holder and having a seat in which said bearing is mounted whereby said holder may be moved about its 20 spherical center to adjust the lamp with relation to the reflector, and means operative beneath and co-acting with a spherically formed bearing constituting the bottom of said member to grip and retain said holder 25 in such adjusted position.

5. In a focusing device, in combination with a reflector, a lamp and a lamp socket having a shank extending therefrom, a holder carrying said socket the shank of 30 which is movable longitudinally in said holder, mechanism comprising in part a movable block adapted to be forced against said shank to secure the socket against such movement, and means co-operating with said 35 block to exert yielding pressure on said shank and thereby prevent too free movement thereof when the same is otherwise free for adjustment.

6. In a focusing device, in combination 40 with a reflector, a lamp and a lamp socket having a shank extending therefrom, a holder carrying said socket the shank of which is movable longitudinally therein, said holder having an upstanding member 45 provided with a partially screw threaded bore therethrough, a movable block operative in said bore and adapted to impinge said shank, a chambered screw threaded plug operative in said bore and adapted to force 50 said block against said shank, and a spring located in said chamber adapted to exert yielding pressure on said block thereby to prevent too free movement of the shank when the screw pressure is relieved.

55 7. In a focusing device, in combination, a socket holder having a bearing constituting a portion of a sphere, a support carrying a member having a seat corresponding with said bearing and in which said holder 60 is mounted, said member being also provided with a lower bearing corresponding with said seat and having a passage-way

therethrough, a rod extending from said holder through and below said member, a washer having a seat conforming to and co-acting with said lower bearing, mechanism 65 co-operating with said washer and said rod to tighten and retain said holder against movement in its seat in said member, and means co-operating with said mechanism 70 adapted to exert yielding pressure against said washer thereby to prevent too free movement of said holder when the same is otherwise free for adjustment.

8. In a focusing device, in combination 75 with a reflector, a lamp and a socket therefor having a shank adapted to slide in a holder, a holder for said shank, a device for securing said shank against movement in said holder, the said holder being provided 80 with a bearing constituting a portion of a sphere, a member having a seat registering with said bearing and in which the holder is mounted, said member being also provided with a lower bearing corresponding 85 with said seat and having a passage-way therethrough, a support for said member, a rod extending from said holder through and below said passage-way, a washer having a seat conforming to and co-acting with said 90 lower bearing, and means co-operating with said washer and said rod to tighten and retain said holder against movement in its seat in said member.

9. As a new article of manufacture constituting a component part of a focusing device, a ring adapted to be secured to a reflector and carrying a member having a seat partaking of the form of the surface of a portion of a sphere and adapted to 100 receive a socket holder, the bottom of said member comprising a bearing conforming to the contour of said seat, the said member being provided with a passage-way through the vertical center line of said seat and said 105 bearing.

10. As a new article of manufacture constituting a component part of a focusing device, a member having a seat partaking of the form of the surface of a portion of a sphere and adapted to receive a socket 110 holder, the bottom of said member comprising a bearing conforming to the contour of said seat, the said member being provided with a passage-way through the vertical 115 center line of said seat and said bearing.

In testimony whereof, I affix my signature in the presence of two witnesses this 7th day of September, 1918.

JOHN KIRBY, JR.
